(57) **CLAIM**

The ornamental design for a cover for portable electronics, as shown and described.

DESCRIPTION

FIG. 1 is a front elevation view of a cover for portable electronics;

FIG. 2 is a rear elevation view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a perspective view showing the design in use; and,

FIG. 8 is a reference view of the design shown in use.

The broken lines shown in the figures are for illustrative purposes only and form no part of the claimed design.
